No. 694,132.

Patented Feb. 25, 1902.

J. & J. A. BUTKUS.
BOTTLE STOPPERING MACHINE.

(Application filed Oct. 14, 1901.)

(No Model.)

UNITED STATES PATENT OFFICE.

JOSEPH BUTKUS AND JOHN A. BUTKUS, OF BALTIMORE, MARYLAND.

BOTTLE-STOPPERING MACHINE.

SPECIFICATION forming part of Letters Patent No. 694,132, dated February 25, 1902.

Application filed October 14, 1901. Serial No. 78,607. (No model.)

To all whom it may concern:

Be it known that we, JOSEPH BUTKUS and JOHN A. BUTKUS, citizens of the United States, residing at Baltimore, in the State of Maryland, have invented certain new and useful Improvements in Bottle-Stoppering Machines, of which the following is a specification.

This invention relates to machines for inserting and fastening stoppers in bottles, and is an improvement particularly in the machine of this character for which we obtained United States Letters Patent No. 681,949, dated September 3, 1901.

15 The object of the invention is to provide a machine such as the patented one just referred to with improved means for pressing a cup-shaped metallic stopper in the neck of a bottle and holding it to its seat in said neck while expanding devices force the ductile metallic side walls of the stopper-body into an annular groove or under an annular shoulder formed in the bottle-neck just below the upper edge of the same.

25 The bottle and stopper for which our improved machine is especially designed is substantially the same as that shown and described in our United States Patent No. 671,263, dated April 2, 1901.

30 Reference is to be had to the accompanying drawings, in which—

Figure 1 is a vertical sectional view, with parts in side elevation, of the upper portion of a bottle-stoppering machine provided with the improved stopper-pressing device. Fig. 2 is an enlarged sectional view taken at right angles to Fig. 1 and illustrating the devices for holding, pressing, and expanding the stopper in their lowered and contracted position. 35 Fig. 3 is a similar view of said parts, illustrating them in the relative positions they assume when the stopper has been expanded in the bottle-neck. Fig. 4 is a detail elevation of the stopper-pressing device with the shouldered sleeve for spreading apart the stopper-holding fingers. Figs. 5 and 6 are detail section views of the stopper respectively before and after it has been expanded.

40 The aforesaid patented machine, for whose entire detail construction reference should be made to our Patent No. 681,949, comprises a hollow standard A, provided at its upper end

55 with a forwardly-projecting ledge a², from which depend the stopper-expanding devices C. Mounted on the top of the standard A is a horizontal shaft e, intended to be rotated by any suitable means, and a wheel k is fixedly held on said shaft and is provided with a cam g⁵, which when the shaft rotates strikes and rocks the lever G, whose forward arm is 60 connected to a wedge-pin c, thereby raising the latter when the lever is rocked. The said wedge-pin when it is raised by said lever has a wedge action on the inside of expanding-fingers c', which expand the ductile metallic 65 side walls of the stopper-body into an annular groove or under an annular shoulder formed in the neck of a bottle.

70 The stopper-expanding devices C comprise a vertical tube c², of spring metal, secured rigidly in and depending from the ledge a² of the standard A, as shown in Fig. 1, and surrounding the wedge-pin c. The said tube is provided with a plurality of vertical slits c³, extending to the lower end thereof, whereby to form a series of spring expanding-fingers c'. Surrounding the stopper-expanding tube c² is a stopper-pressing tube b, which is the principal device of the present invention. 75 This stopper-pressing tube at one end is exteriorly screw-threaded, as shown in the drawing at b⁵, and is screwed into a screw-threaded opening b' in the standard-ledge a², whereby said stopper-pressing tube may be vertically 80 adjusted independently of the expanding-tube c². A lock-nut b² holds said pressing-tube at different vertical adjustments. The stopper-pressing tube b is made of spring metal and is provided with a plurality of longitudinal slits b³, extending to the end opposite that which is threaded, whereby said slotted end forms pressing-fingers b⁴, that can expand and contract slightly, and said slotted tube extends downwardly to within a short 85 distance of the lower ends of the stopper-expanding fingers c', as indicated in the drawings.

90 Mounted on the stopper-pressing tube b is a stopper-releasing sleeve l, which is held by screw-threads d in engagement with said tube b at different vertical adjustments, and the lower edge d' of said stopper-releasing sleeve is beveled, whereby to form a shoulder for engagement with shoulders l⁴, formed on the 95

inner sides of the spring-fingers l^3 of the stopper-holding tube l^2 , which is mounted to slide up and down on the releasing-sleeve l . The lower ends of the spring stopper-holding fingers l^3 are beveled on their inner sides, as at f , whereby they will spread apart and automatically spring back when a stopper is pushed up within the circle of said fingers, and the latter are also provided above the bevels f with shoulders l^5 for the upper edge of the stopper to rest on when it is inserted within the circle of the fingers. An opening l^6 , corresponding in contour to the cross-sectional shape of the stopper, is formed at one side and at the lower end of the stopper-holder, through which the stoppers may pass from the discharge-chute d^7 of stopper-feeding devices D , so that the stoppers may be fed automatically to the expanding devices, and a downwardly-spring-pressed casing L is rigidly secured to and surrounds the stopper-holder, so as to move with the same, and is provided with a side opening l^{11} to admit the stoppers from the feeding devices. The casing L is intended to receive the mouth of a bottle, as indicated in Fig. 3, so as to guide it into position to receive the stopper.

After a stopper has been passed, either by hand or by the automatic feeding devices, into the stopper-holding tube, with the rim h' of the stopper resting on the shoulders l^5 , a bottle that is to be stoppered is pushed upwardly into the lower end of the casing L and raises said casing and the stopper-holder. This movement causes the shoulders l^4 of the stopper-holding fingers to ride upon the annular shoulder d' of the stopper-releasing sleeve l just after the expanding-fingers enter the stopper, thereby spreading the stopper-holding fingers l^3 apart and allowing the stopper to drop into the mouth of the bottle, which is just beneath and almost in contact with the stopper at that time. The bottle continues to rise until the lower ends of the pressing-fingers come into contact with the top rim h' of the stopper, and said pressing-fingers by resisting the upward movement force the stopper to its seat in the bottle-mouth, which compresses and wedges the sealing-collar h^2 between the inclined interior wall α of the bottle-mouth and the vertical side wall of the stopper and at the same time slightly mashes in the ductile metallic side walls by reason of the contracting of the pressing-fingers as they slide downwardly and inwardly on the inclined wall of the bottle-mouth. Immediately thereafter the wedge-pin c commences to rise and spread apart the expanding-fingers, so that the latter will expand and stretch the metal of the stopper-body into the groove in the bottle-mouth, and thereby fasten the stopper in the same. The pressing-fingers b^4 , although they are unyielding longitudinally, can yield laterally to a slight extent, so that they will be pressed together as their ends slide on the inclined wall α of the bottle-mouth, and thereby they readily press the stopper.

fully to its seat and do not tend to break the bottle. By vertically adjusting the stopper-pressing tube b its lower end will be raised or lowered, so that it will always push a stopper until the bottom thereof passes the groove in the bottle-mouth, and by vertically adjusting the stopper-releasing sleeve l the stopper-holding fingers may be caused to release the stopper when the bottle is just underneath the latter, thereby compensating for stoppers of slightly-different height and preventing the bottle-mouth from mashing the stopper-holding fingers and the stopper while it is held therein.

Referring to Figs. 5 and 6 of the drawings, it will be seen that after the stopper has been expanded in the bottle-mouth the side walls of the bottle-stopper are mashed in slightly from their primary vertical condition. This facilitates the withdrawal of the stopper from the bottle-mouth by affording an inclined surface for an opener to engage with, as indicated in Fig. 6.

Having thus described our invention, what we claim as new, and desire to secure by Letters Patent, is—

1. In a bottle-stoppering machine, the combination of stopper-expanding devices; a stopper-pressing device surrounding said expanding devices; a vertically-reciprocable stopper-holding device surrounding said stopper-pressing device and adapted to hold a stopper below the latter and the expanding devices; and means for releasing the stopper from said stopper-holding device.

2. In a bottle-stoppering machine, stopper-expanding devices; and a vertically-adjustable stopper-pressing device surrounding said expanding devices, as set forth.

3. A device for fastening a cup-shaped ductile metal stopper in a bottle-mouth, provided with stopper-expanding fingers; and a laterally-yielding stopper-pressing device adapted to press the stopper in the bottle-mouth while it is being expanded.

4. A bottle-stoppering device comprising a tube provided with a series of expanding-fingers; means for spreading said fingers apart; and a tube, b , surrounding said first-named tube and provided with a series of fingers adapted to press the stopper into a bottle-mouth, as set forth.

5. In a bottle-stoppering machine, a tube provided with a series of expanding-fingers; means for spreading said fingers apart; and a stopper-pressing device surrounding said tube and vertically adjustable with respect to the same, as and for the purpose set forth.

6. In a bottle-stoppering machine, the combination with the standard and its projecting ledge, of a tube secured to and depending from said ledge and provided with a series of expanding-fingers, means for spreading said fingers apart; and a stopper-pressing tube held vertically adjustable in said ledge and surrounding said first-named tube.

7. In a bottle-stoppering machine, the com-

5 bination of a stopper-expanding device pro-
vided with a series of spring-fingers; means
for spreading said fingers apart; a stopper-
pressing tube surrounding said expanding-
fingers; a stopper-releasing sleeve surround-
ing said pressing-tube and provided with an
annular shoulder; and a vertically-recipro-
cable stopper-holding tube provided with fin-
gers which are formed with shoulders, adapt-
ed to engage said annular shoulder whereby
10 said fingers may be spread apart and release
the stopper, as set forth.

15 8. In a bottle-stoppering machine, the com-
bination of a stopper-expanding device pro-
vided with a series of spring-fingers; means
for spreading said fingers apart; a stopper-
pressing tube surrounding said expanding-
fingers; a vertically-adjustable stopper-re-
leasing sleeve surrounding said pressing-tube
20 and provided with an annular shoulder; and
a vertically-reciprocable stopper-holding tube
provided with fingers which are formed with
shoulders, adapted to engage said annular

shoulder whereby said fingers may be spread
apart and release the stopper, as set forth. 25

9. In a bottle-stoppering machine, the com-
bination of a stopper-expanding device pro-
vided with a series of spring expanding-fin-
gers; means for spreading said fingers apart;
a vertically-reciprocable stopper-holding tube 30
provided with fingers formed on their inner
sides with shoulders, ⁷⁴; and a vertically-ad-
justable stopper-releasing sleeve interposed
between said expanding-fingers and stopper-
holding fingers and provided with a shoulder
35 adapted for engagement by the said shoul-
ders, ⁷⁴, of the stopper-holding fingers, as set
forth.

In testimony whereof we affix our signa-
tures in the presence of two witnesses.
